UNITED STATES PATENT OFFICE.

AUGUSTINE C. WEST, OF CAMBRIDGE, ASSIGNOR OF ONE-HALF TO PAGE
BROTHERS & CO., OF BOSTON, MASSACHUSETTS.

OIL-STOVE.

SPECIFICATION forming part of Letters Patent No. 506,143, dated October 3, 1893.

Application filed June 20, 1892. Serial No. 437,336. (No model.)

To all whom it may concern:

Be it known that I, AUGUSTINE C. WEST, of Cambridge, in the county of Middlesex, State of Massachusetts, have invented certain new and useful Improvements in Oil-Stoves, of which the following is a description sufficiently full, clear, and exact to enable any person skilled in the art or science to which said invention appertains to make and use the same, reference being had to the accompanying drawings, forming part of this specification, in which—

Figure 1 is a front elevation of my improved oil-stove; Fig. 2 a central vertical longitudinal section of the same; Fig. 3 an end elevation; Fig. 4 a vertical transverse section enlarged of the lamp burner; Fig. 5 a side elevation partly broken away of the lighter sleeve detached; Fig. 6 a side elevation of the outer wick tube removed, and Fig. 7 sectional views illustrating the shelfe hinges.

Like letters and figures of reference indicate corresponding parts in the different figures of the drawings.

My invention relates especially to a construction of the body of an oil stove and the mechanism for furnishing heat for the same, the object being to greatly decrease the cost while producing a device free from the objectionable features of "sweating" and heating of the oil tank and burner incident to the use of many stoves of this class.

The nature and operation of the improvement will be readily understood by all conversant with such matters from the following explanation:

In the drawings, A represents the burner mechanism considered as a whole and B the stove. The stove comprises a horizontal wooden shelf, b, supported on wooden legs, d. From each end of this wooden shelf a vertical standard of sheet metal, f, projects and supports the top, h, of the hot air box, C. This top has a series of the ordinary stove-holes, g, and is preferably constructed of cast iron. The hot-box is completed by a bottom, i, which may be bolted centrally to the top at 100 (see Fig. 2) and by sides, 101, engaging said top. In the bottom, i, there are one or more openings, J, for the stove chimneys. Outside the box the standards are

connected by supporting bands, 102. The top projects longitudinally at, k, beyond the standards, f, and at each side a hinged shelf, m, (see Figs. 3 and 7) is mounted. These shelves have a double hooked hinge-leaf, p, which is adapted to take in an opening, q, formed in the pendent flange, r, of the top, h. The hook, t, of the leaf is designed to support (see Fig. 7) said shelf when lowered as represented by dotted lines in Fig. 3. The shelf is supported in horizontal position by a notch, v, at the opposite side of said leaf which takes on a projection, w, on the under side of the main top, h. The upper face of the wooden shelf, b, is covered by a facing, x, of sheet metal. The oil-tank or reservoir, D, is secured to the under face of said shelf supported by lugs, y. A filler opening and nipple, z, (Fig. 2) leads into the rear of the tank. The shelf, b, is provided with openings, 15, for the body of the burner mechanism. This body comprises an outer cylinder, 20, which is disposed in the opening, 15, of the shelf, b, and extends through the bottom 75 of the reservoir, D. Near its lower end the body, 20, has a series of perforations or openings, 21, through which the oil flows. The wick-tube, E, (see Fig. 4) comprises an outer tube, 22, and an inner tube, 24, secured to 80 the outer tube by an annulus, 25. A ring, 104, connects the outer tube with the cylinder, 20, said cylinder being soldered rigidly into the bottom of the reservoir. The inner tube opens through the bottom of the tank. 85 The outer tube is provided with perforations, 26, near its lower end while the inner tube, 24, is solid. Said outer tube is shown in detail in Fig. 6. A wick-sleeve, 27, comprising a cylinder of perforated metal, is fitted to 90 slide vertically between the tubes, 22, and, 24, the wick, 28, being secured to said sleeve. The outer tube, 22, is provided with a series of slotted openings, 29, and journaled in said outer tube and the body, 20, there is an ordinary wick-shaft, 30, bearing the pinion, 13, which meshes in the sleeve, 27, whereby said sleeve is moved to raise and lower the wick. The body, 20, is provided adjacent its upper end with an outwardly projecting bead, 100 31, upon which a cylindrical perforated air-distributer, 32, rests, said distributer being

either fast or removable as preferred. An inwardly projecting bead, 33, is formed at the top of the body, 20, and an inwardly sloping annulus, 34, is mounted thereon, said 5 annulus closely encircling the outer wick-tube, 22, without touching leaving a narrow air-space, 105, which prevents heat being transmitted from the outer tube, 22, to the body, 20, by said annulus. The inner wick-tube, 24, has an annular inwardly projecting bead, 35, which supports the flame spreader, F. Said spreader comprises a ring, 36, which rests on said annulus and fits tightly into the inner tube. From the upper edge of said 10 ring an inverted cone of foraminous material, 37, is pendent, the apex, 38, of the cone when in position being disposed centrally within the inner wick-tube. From the base of the cone outwardly flaring annular perforated walls, 39, project vertically, their top 15 being covered by a solid disk, 40. Said disk is connected centrally by a rod, 41, with the apex, 38, of the cone.

The chimney-holder, H, shown in detail in 20 Fig. 5, comprises a combined lighter and insulator to prevent the heat from the chimney being conveyed to the body, 20, of the wick-tubes, E. The holder comprises a cylinder, 50, of perforated material which is fitted to 25 slide and rotate on the outer wick-tube, 22, above the annulus, 34, on the body, 20, said cylinder resting on the inner edge of said annulus, as best shown in Fig. 4. The cylinder is of such length that its top projects above 30 the top of the distributor, 32. A horizontally-arranged ring or annulus of perforated material, 51, is secured to the cylinder, 50, and when the holder is in position projects outward from the top of the distributor, 32, leaving a space, 52, between, as shown in Fig. 4. The walls of the cylinder, 50, are provided 35 with one or more openings, 53, of size suitable to admit a match and in such position that when the holder or lighter is elevated 40 these openings will register with the top of the wick as shown in the view of the heater at the right in Fig. 1.

The holder proper, 55, is secured to the outer edge of the perforated annulus, 51. Said holder proper comprises a ring vertically curved so that its upper edge, 56, (see 45 Fig. 4) projects slightly above the top of the outer wick-tube, 22, leaving a space, 57, between. The ring curves vertically downward 50 forming a groove, 58, in which the chimney, J, rests. In the bottom of the groove a series of indentations or bosses, 59, are punched, which rest on the annulus, 51, and by which the ring, 55, is secured to said flange. This 55 forms only slight points of contact between the solid ring, 55, of the holder and the perforated ring, 51, air-spaces, 60, being left between the bosses. The outer edge of the ring, 55, is bent vertically downward at, 61, forming 60 an annular flange which slightly overlaps without contacting the top of the perforated distributor, 32. A finger-piece or knob, 62, is

secured to the pendent flange, 61, whereby the chimney-holder may be rotated and elevated. The chimney, J, rests in the groove, 58, and projects through the opening, J, in the bottom of the hot-air box, C. Said chimneys are provided preferably with one glazed opening, 65, (see Fig. 1) located opposite the top of the wick. To light the wick by means 70 of the finger-piece, 62, the chimney, H, may be rotated and elevated on the outer wick tube, 22, until the lighter openings, 53, of its cylinder, 50, register with the wick-top and are exposed above the top of the distributor 75 cylinder, 32. A lighted match may be inserted in said openings the wick ignited and the holder dropped to its normal position. By rotating the holder the chimney may be arranged so that its glazed opening will throw 80 the light in any desired direction. One end wall of the box, C, and the standards, f, are provided with draft-openings, 70.

In use, the wick being lighted, the disk, 40, of the spreader, F, distends the flame laterally. Cold air drawn by the heat of the flame through the inner wick tube, 24, passes through the perforated cone, 37, of the spreader and out through the flaring perforated portion, 39, to the inner side of the flame, greatly 90 intensifying the heat and promoting combustion. This construction of spreader also serves to so break up the current of air through the inner wick or draft tube that the flickering of the flame is prevented. The 95 heat of the chimney causes a current of cold air to be drawn through the cylindrical distributor, 32, the current thence passing through the horizontal perforated plate, 51, of the holder and through the opening, 57, 100 between said holder and the outer wick tube. The current being broken by the perforated portions through which it passes reaches the flame on the outer side adjacent the wick steadily and without causing it to flicker. 105 The heat from the chimney, while sufficient to create a draft or current of air in the manner described, is prevented from heating either the cylindrical distributor, 32, or the 110 body cylinder, 20, connected with the oil reservoir, by means of the air-space, 52. The 115 perforated cylinder, 50, of the chimney holder and the perforated ring, 51, secured thereto also afford such air-space that heat cannot be imparted in any appreciable degree to the 120 body, 20, or oil reservoir. The air-spaces, 60, between the bosses in the bottom of the groove, 58, of said holder serve as additional 125 means for effecting this result. It is found by thus constructing the burner and chimney 130 holder that said burner is kept at a very low temperature even though the chimney and the holder-ring, 55, may have attained a high degree of heat, it being possible practically to at any time handle the distributor, 32, 135 while the wick is burning. The flame being fed by air on its inner and outer side disburses an intense heat to the box, C.

To prevent the top of the oil-reservoir, D,

from becoming affected by the heat reflected from the outside of the chimney I interpose the wooden shelf, *b*, described. This non-heat conducting substance although faced with the metal, *x*, is practically an absolute preventative from any heat reaching the oil in said reservoir and all objections from the same "sweating" are obviated, no heat being imparted to said oil through the body, 5 20, on account of the air-spaces and arrangement of the burner above described. In addition, the use of the wooden shelf mounted on wooden legs, a construction and employment of material attended with serious objections in oil-stoves of common construction, 25 greatly cheapens the cost when employed as in my improvement and renders the stove lighter and stronger. Any number of holes, *g*, may be formed in the top, *h*, and only one 20 burner may be employed, if preferred. The hot-air box may be supported by single standards at its corners instead of the broad sheet metal standard shown. The hinged shelves, *m*, when lowered form a hot space around the 25 chimneys greatly increasing the efficiency of the device for heating by radiation. It will be understood that a feed-wick, 80, represented by section lines in Fig. 4, may be disposed around the outer wick tube, 22, so that 30 when the wick, 28, becomes short it can be fed by means of said wick, 80, through the slots, 29, in the outer wick tube.

Having thus explained my invention, what I claim is—

35 1. In an oil stove the combination of a suitably supported wooden-shelf forming a base and having a metallic-plate on its upper face, and an oil reservoir suspended from its under face substantially as and for the purpose 40 set forth.

2. In an oil-stove the combination of a wooden shelf forming a base with a metallic covering on its upper side said covering and

shelf being provided with one or more openings; an oil reservoir supported from the under side of said base and the cylinder or heater body disposed in said openings. 45

3. In an oil-stove a wooden-shelf and an oil reservoir supported from said shelf in combination with the cylinder, 20, and wick-tube, 50 *E*, extending through said shelf and reservoir and a central draft burner supported thereon.

4. In an oil-stove the shelf and reservoir in combination with the body of the burner 55 mechanism opening through said shelf and reservoir; a hot-air box supported on said shelf; and a flue or chimney connecting the burner-mechanism with said box.

5. In an oil-stove a shelf or base of non- 60 heat conducting material having a metallic facing on its top in combination with an oil reservoir secured to the under face of said shelf; a hot-air box supported on said shelf; a central draft heater mechanism having its 65 body opening through the shelf and reservoir; and a flue or chimney connecting the heater and box, substantially as and for the purpose set forth.

6. In an oil-stove the base in combination 70 with the hot-air box supported thereon and provided with the top, *h*, having the lug, *w*; the shelf, *m*, provided with the double-hooked hinge-leaf, *p*, adapted to take in an opening, *q*, in said lug.

7. In an oil-stove the shelf and reservoir in combination with the heater supported therein; a chimney-holder on said heater provided with lighter-openings and fitted to be rotated and moved vertically on the wick-tube of 80 said heater substantially as described. 75
